MOBILE INSTRUMENT CONSOLE

James R. Belknap, Syracuse, N.Y., assignor to Beckman
Instruments Inc., a corporation of California

Filed June 13, 1962, Ser. No. 70,526

Term of patent 14 years

(Cl. D26—5)

FIG. 1 is a perspective view of a mobile instrument console, showing my new design.

FIG. 2 is a front view of a console shown in FIG. 1;

FIG. 3 is another perspective view of the console embodying the invention; and

FIG. 4 is a side view of the console shown in FIGS. 1, 2 and 3.

The essential features of my design reside in the portion shown in full lines.

I claim:

The ornamental design for a mobile instrument console, substantially as shown and described.
